SECTIONAL BOILER WITH SUPERHEATER

Filed June 14, 1947

UNITED STATES PATENT OFFICE

2,516,057

SECTIONAL BOILER WITH SUPERHEATER

William Knox, Jersey City, N. J.

Application June 14, 1947, Serial No. 754,740

2 Claims. (Cl. 122—225)

1

This invention relates to heating devices and particularly to steam boilers of the lower pressure type. Among the objects of the invention is to provide a single block steam generating section adapted to be connected with another steam generating section or sections to provide therewith a combustion space and communicating water and steam spaces of a steam boiler, and in which the single section is provided with conduit means communicating with the steam space and extending into the combustion space of the boiler for exposure to the products of combustion and thence to the steam outlet of the boiler, thereby to improve the quality of the steam or superheat it and effect operational economies.

Another object of the invention is to provide a single block section adapted for attachment to an intermediate section of a conventional sectional low pressure steam boiler and providing the steam outlet for the boiler and containing steam conduits for conducting the steam generated in the boiler from the steam space through a conduit means or manifold exposed to the products of combustion and thence to the steam outlet; whereby, in order to convert a conventional sectional low pressure steam boiler into one capable of producing steam of high quality, all that is required to be done is to substitute the improved block section for the end block section of the conventional sectional boiler. The improved block section embodies substantially integrally associated steam passageways and attached conduit means or manifold communicating with the passageways and arranged for extension into the combustion space or firebox.

A further object of the present invention is to provide for the making of some steam when a minimum amount of heat is being supplied, for example, when the fire is banked for the night in a conventional residence installation. Under such circumstances it is desirable that some steam be supplied to the radiation system to prevent the house getting too cold. The present invention further provides a water-containing header means, preferably arranged below the steam conducting conduit means or manifold hereinabove described, and which is close to the place in the boiler where the heat is generated, as close over the normal position for a fuel bed. Thus it provides for the steady generation of a small amount of steam, even with a small or minimum generation of heat and with a minimum combustion rate of fuel.

Other objects of the invention will appear from the following explanation of the principle

2

of the invention and the best mode in which I have contemplated applying that principle.

In the drawings,

Fig. 1 is a perspective view of a domestic type sectional steam boiler embodying a single end block section of the present invention;

Fig. 2 is a horizontal section substantially on line 2—2 of Fig. 1;

Fig. 3 is a fragmentary vertical section on line 10 3—3 of Fig. 2;

Fig. 4 is a fragmentary vertical section on line 4—4 of Fig. 2; and

Fig. 5 is a showing, in vertical section, of a modified form of the invention comprising a water-containing header means in communication with the end block section and the steam manifold.

As in the usual case of a sectional steam boiler, intermediate sections 1, 2, 3, 4, 5, 6, etc., in the 20 desired number, are joined together in series arrangement with their water and steam spaces respectively connected together. The front end block section 1 is provided with the usual firebox door 8, cleaning doors 9 and 10 and ash pit door 11. The rear end block section in the conventional sectional boiler usually has a water inlet, a steam outlet, and an opening for the discharge of products of combustion. All of the sections are held in assembled relationship by tie-rods, such as tie-rods 12 and 13. The vertical and top portions of the intermediate sections and the greater portions of the end block sections are hollow for containing water and steam as is well understood. The inner walls of the assembled section enclose a firebox which may be provided with a grate 14 should solid fuel be used. The intermediate sections are commonly provided with hollow crossing auxiliary portions 15, 16, 17, etc., below the water line and above the firebox or combustion chamber.

40 In the steam boiler of the present invention the customary intermediate and front end block sections are utilized, as, for example, of the type hereinabove described, or of equivalent types. The rear end block section 18, though having a hollow wall enclosing a water space 19 and a steam space 20 which are contiguous at a desired water level and respectively communicating with corresponding spaces of the adjacent 45 intermediate section 6, is provided with means for conducting and heating all of the steam generated in the boiler. This means includes a vertical passageway 21 in open communication with the steam space 20 at its upper end through an opening 22, a cored passageway 23 through the 50 double wall of the rear end block section 18 (Fig.

3), a conduit means or manifold 24 (Figs. 1 and 2), a cored passageway 25 through the double wall of the end block section 18, and a vertical passageway 26 discharging to a steam delivery outlet and riser 27 (Fig. 4). Passageways 21, 23, 25 and 26 may be and preferably are cast integrally with the rear end block section 18. Each of vertical passageways 21 and 26 is provided with an opening 28, 29, which is normally closed by a plug, whereby the headers of the conduit means or manifold 24 may be cleaned.

The conduit means or manifold 24 is supported by the end block section 18 and is so disposed as to extend into the firebox of the boiler or in external contact with the products of combustion. The manifold is removably fastened to nipples 30 and 31 which are threaded into passageways 23 and 25, respectively. The nipples are coupled to headers 32 and 33, respectively, by disconnectable flanged couplings. The conduit means or manifold 24 includes the headers 32 and 33 which are closed at their ends at 34 and 35 respectively and are connected together by a number of tubes 36, 37 and 38 through which the steam travels from header 32 to header 33. The nipples, headers and tubes of the conduit means or manifold 24 are made of wrought iron or steel and the tubes are joined to the headers by welded connections.

The conduit means or manifold 24 is preferably located above the source of heat; and all of the steam generated in the boiler is thereby subjected to radiation as well as to the products of combustion rising from the bed of fire or flame before delivery to the riser. The end block section 18 may be provided with a tapped hole 39 for receiving a feed water pipe 40, and with a suitable flue opening 41.

In Fig. 5 there is illustrated a modified form of the invention in which the heating surface of the boiler is increased by providing a water-containing header means 42 immediately below a steam header 43 which latter corresponds generally to the conduit means 24. The headers 42 and 43 are connected by tubes 44 and 45 which are welded to the respective headers. The water-containing header means 42 is coupled to a nipple 46 which is engaged in a cored passageway 47, cast in the rear end block section 48. Block section 48 corresponding generally to the end block section 18 of the preceding figures also has a water outlet 49, which is connected by a pipe 50 to a float level control valve means 51 and thence to passageway 47, whereby the water-containing header means 42 is kept filled with water automatically. Normally the controlled level of water would be such as to fill the water-containing header means and no higher. Any suitable type of level maintaining means, many of which are known to the art, may be used as the level control valve means 51. The details of this means form no part of the present invention.

The water-containing header means 42 is situated close to the source of heat in the boiler and it is therefore capable of generating steam even though the fire be banked at night, as is customarily done in a residential installation. Even though only a minimum amount of heat is being maintained in the boiler, the apparatus shown in Fig. 5 will provide some steam to the heating system and prevent the house from getting too cold.

Preferably, the water-containing header means 42 is connected to the steam header 43, which is in a position corresponding to steam header 32 in the arrangement shown in Figs. 1 to 4, inclusive. The steam conduit means or manifold used

in conjunction with the water-containing header means 42, functions in the manner hereinabove described. Auxiliary brackets may be provided, if desired and in a manner not particularly illustrated, for contributing to the support of the conduit means or manifold and water-containing header means 42.

What is claimed is:

1. In a domestic type, sectional steam boiler, in combination, a single section providing a water space and a steam space communicating therewith, said spaces being contiguous to one another at a water line, said single section being adapted to cooperate with a plurality of other sections together making up such boiler and providing a combustion space and a passage for products of combustion therefrom, a steam header arranged to be in contact externally with products of combustion generated in said combustion space and connected to and supported at least in part by said single section, said steam header serving to conduct vapor and steam from an inlet to an outlet therefor, means connecting the steam space of said single section above the water line with the inlet to said steam header, means connecting said outlet of said steam header to a steam delivery outlet from said boiler, a water-containing header means exposed externally to the products of combustion in said boiler and located at a level lower than that of said steam header, said water-containing header means communicating with the water space of said boiler below the water level thereof, means for conducting water into said water-containing header means from the water space of said boiler, said water-conducting means including control means to maintain a water level in said water-containing header means and at a predetermined point below said steam header, and means connecting said water-containing header means with said steam header.

2. A steam generating and heating unit for a sectional boiler, comprising, in combination, an end block section providing a water space and a steam space, a steam header arranged to be in contact externally with products of combustion, connected to said end block section and serving to conduct vapor and steam from an inlet to an outlet therefor, means connecting the steam space of said end block with the inlet to said steam header, means connecting said outlet of said steam header to a steam delivery outlet for the boiler, header means for containing water, means for conducting water into said water-containing header means from the water space of said boiler below the water level thereof, said water conducting means including control means to maintain a water level in said water-containing header means and at a predetermined point below said steam header, and means directly connecting said water-containing header means with said steam header.

WILLIAM KNOX.
